[57] **CLAIM**

The ornamental design for a heat shrinkable capsule for a champagne bottle, as shown and described.

DESCRIPTION

FIG. 1 is a perspective view of a heat shrinkable capsule for a champagne bottle showing my new design; FIG. 2 is a side elevation;

FIG. 3 is a top plan view taken along the line 3—3 in FIG. 2;

FIG. 4 is a side elevation taken in the direction indicated in FIG. 3;

FIG. 5 is a side elevation taken in the direction indicated in FIG. 3; and

FIG. 6 is a bottom plan view.

The dash lines in FIGS. 1, 2, 3, 4 and 6 represent score lines.
